(57) **CLAIM**

The ornamental design for sleeve cover for targets of different sizes, as shown and described.

DESCRIPTION

FIG. 1 is a perspective view of a sleeve cover for targets of different sizes.

FIG. 2 is a front view of the sleeve cover of FIG. 1.

FIG. 3 is a left side view of the sleeve cover of FIG. 1.

FIG. 4 is a right side view of the sleeve cover of FIG. 1.

FIG. 5 is a top view of the sleeve cover of FIG. 1.

FIG. 6 is an exploded view of the sleeve cover removed from a conventional target being illustrated in broken lines.

FIG. 7 is a left side view of a sleeve cover stretched over and conforming to a first size conventional target; and, FIG. 8 is a left side view of the sleeve cover of FIG. 7 stretched over and conforming to a second size conventional target.

The diagonal line pattern within the bounded area represents a low thermal emissivity surface region.

The broken line showing of a Conventional Target is included for the purpose of illustrating environment and forms no part of the claimed design.

The claimed design is for a sleeve cover having a low thermal emissivity surface region and a stretchable material to cover conventional targets of different sizes constructed in accordance with the present invention, where the sleeve cover includes stretchable material, and an opening allowing the sleeve cover to be stretched over and conform to a conventional target.
